UNITED STATES PATENT OFFICE.

MARSHALL C. MUNN, OF LEE, ILLINOIS, ASSIGNOR OF ONE-HALF TO A.
RUDOLPH YOUNGGREN, OF LEE, ILLINOIS.

MACHINE FOR MOLDING FENCE-POSTS.

No. 839,178.

Specification of Letters Patent.

Patented Dec. 25, 1906.

Application filed October 3, 1906. Serial No. 837,194.

To all whom it may concern:

Be it known that I, MARSHALL C. MUNN, a citizen of the United States, residing in Lee, in the county of Lee and State of Illinois, have invented a new and useful Improvement 5 in Machines for Molding Fence-Posts, of which the following is a specification.

This invention relates to a machine for molding metallic fence-posts into artificial stone bases; and it consists in the novel construction of parts and devices and novel combinations of parts and devices hereinafter set forth.

In the accompanying drawings, which 15 form a part of this specification, and in which like numerals of reference indicate like parts, I show at Figure 1 an end elevation of a machine containing my invention; at Fig. 2, a side elevation of the same; at Fig. 3, a 20 vertical cross-section of the machine, taken on the line 3 3 at Fig. 2; at Fig. 4, a vertical longitudinal section of the machine, taken on the line 4 4 in Fig. 1; at Figs. 5 and 6, detached perspective views of the upper and 25 lower sliding and fence-post supporting end-closing pieces; at Figs. 7 and 8, respectively, the lower and the upper halves of the axially-movable mold end, and at Fig. 9 a central vertical section taken on the line 9 9 of Fig. 8.

30 In said drawings, 21 is the semicylindric lower half, and 22 the semicylindric upper half, of the mold. The lower half is shown as made integral with the base of the framework of the machine and as being stationary, 35 while the upper half is shown as being movable up and down or toward and away from the said lower half. This movement is for the purpose of shaping and compressing in a direction at right angles to the mold the concrete or plastic filling of the mold placed in and 40 heaped upon the said lower half of the mold. To retain such plastic material in place and also to afford a guideway for said movable half, the four-sided box is provided, consisting of the two vertical sides 23 24 and the 45 two vertical ends 25 26. One of these ends, 25, is or may be rigidly fixed to the side pieces 23 24. The other is shown as being movable toward and away from the mold in an axial 50 direction, this being for the purpose of forming and compressing the upper end of the molded artificial-stone base. The usual uprights 27 27 27 27 are provided and extend

upward from the base to a point above the upper half of the mold, and they carry the 55 eccentric levers 28 28, by means of which the operator may press the upper half of the mold down upon the lower half with great force to shape the plastic concrete into cylindric form. A similar eccentric lever 29 is 60 connected by rods 30 to the movable end 31, this being for forcing said movable end against the concrete in the mold to shape the same.

The part of the movable end 31, which 65 comes into immediate contact with the concrete is shown at 32 and is preferably given the form of a truncated cone, so that the upper end of the artificial-stone base shall have this form when molded. Extending vertically 70 from the outer surface of the movable end plate 31 are two strengthening-bars 33, rigidly connected to said plate 31 and extending up to bear against the end piece 26 of the upper half of the mold, which end piece 26 is 75 also made movable and carries its half 34 of the conical-end-forming portion. Formed in the movable ends 26 and 31 are guideways 310 for the two vertically-sliding blocks 35 36, the former being the lowermost and the 80 latter being the uppermost. These two blocks are shown in perspective at Figs. 5 and 6, and when they are fitted in place in the end pieces 26 and 31 they come together and leave an aperture 37 of the shape of the 85 metallic fence-post in cross-section.

The metallic fence-post is shown in the drawings at 38, and it is in the present instance of a Y form in cross section.

39 39 40 40 are guided-pins extending 90 from the vertical sides 23 24 and the base 21 and into holes in the movable end pieces 26 31.

41 is a lever pivoted to the base of the machine at 42 and to the sliding piece 35 at 43, 95 and the free end of this lever is brought into frictional contact with a downwardly-depending spring 44, which exerts sufficient holding power to sustain the weight of the sliding blocks 35 36 and the weight of the 100 metallic fence-post, but which does not exert sufficient force to prevent the fence-post from moving up and down in the mold when a superior force is brought to bear upon it. The purpose of having the support of the fence-post in the mold thus made movable up and 105

down is in order that when the pressure of the mold is brought to bear upon the concrete inclosing said fence-post that no bending strain may come to said post. In the 5 machines as heretofore constructed great difficulty was encountered because of this tendency for the fence-post to bend in the mold. As formerly made, the fence-post support in the end of the mold was rigid and unyielding 10 in its relation to the lower part of the mold, and when the concrete was applied to fill the mold and surround the post it very often happened that the end of the post in the concrete would be supported more firmly than 15 the intervening parts of said post, and the result of applying the powerful molding pressure to the concrete above and around said post under such circumstances was to bend the post in the concrete, and when the concrete became set and the mold was opened 20 under such circumstances the resiliency of the metallic post sprung it back into a straight line, and this would split the concrete base. By the simple expedient of 25 making the supporting end of the mold that carries the fence-post thus movable up and down I have entirely overcome this serious difficulty in the machine, and by making the end which carries the movable parts also mov- 30 able endwise of the mold I am enabled to give to the upper part of the molded base a smooth even surface and a desirable conical shape which is adapted to improve the weathering qualities of the post-base. On the up- 35 per end of the lower sliding part 35 are formed lugs 45, and pivoted to the movable end plate 26 are two catches or hooks 46 for engaging the lugs 45 for sustaining the said sliding piece 35. A handle 47 serves to move the 40 hooks or catches into or out of engagement by swinging the lever on its fulcrum 48.

I claim—

1. The machine for molding bases on metallic fence-posts having a stationary half-mold and a movable half-mold, and means for forcing the movable half-mold on the plastic material, and having at one end of the mold a movable support for the metallic fence-post capable of yielding to prevent 45

bending strains in said post due to the com- 50 pression, substantially as specified.

2. The machine for molding bases on metallic fence-posts having a stationary half-mold and movable half-mold, and means for forcing the movable half-mold on the 55 plastic material and having the end which supports the metallic fence-post made movable toward and away from the concrete, in order to shape and compress the upper end of the artificial-stone fence-post base, substan- 60 tially as specified.

3. The machine for molding bases on metallic fence-posts having a stationary half-mold and a movable half-mold, and means for forcing the movable half-mold on the 65 plastic material, and having at one end of the mold a movable support for the metallic fence-post capable of yielding to prevent bending strains in said post due to the com- 70 pression, said movable support being frictionally supported, substantially as specified.

4. The machine for molding bases on metallic fence-posts having a stationary half-mold and a movable half-mold, and means for forcing the movable half-mold on the 75 plastic material, and having at one end of the mold a movable support for the metallic fence-post capable of yielding to prevent bending strains in said post due to the com- 80 pression, said movable support being frictionally supported by means of a lever and a friction-spring, substantially as specified.

5. The machine for molding bases on metallic fence-posts having a stationary half-mold and a movable half-mold, and means 85 for forcing the movable half-mold on the plastic material and having the end which supports the metallic fence-post made movable toward and away from the concrete in order to shape and compress the upper end of 90 the artificial-stone fence-post base and having means for forcing said movable end on the plastic material in the mold, substantially as specified.

MARSHALL C. MUNN.
